(57) **CLAIM**

The ornamental design for a hammer, as shown and described.

DESCRIPTION

FIG. 1 is a rear, bottom, right-side perspective view of the hammer

FIG. 2 is a right-side elevational view thereof; and

FIG. 3 is a top plan view thereof;

FIG. 4 is a front elevational view thereof;

FIG. 5 is a rear elevational view thereof;

FIG. 6 is a left-side elevational view thereof; and,

FIG. 7 is a bottom plan view thereof.

The broken lines depict unclaimed portions of the hammer, and thus form no part of the claimed design.

1 Claim, 4 Drawing Sheets

FIG. 1

FIG. 4

FIG. 5
